(57) **CLAIM**

The ornamental design for cartridge for mixing machines, as shown and described.

DESCRIPTION

FIG. 1 is a perspective view of a cartridge for a mixing machine with the handle in the open position showing the new design for a cartridge for mixing machines;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings are shown for illustrative purposes only and form no part of the claimed design. In addition, the surface shading illustrated in the drawings is provided merely to highlight contour of design; it is not intended to be illustrative of texture or gloss.
